OIL BURNER

Leslie W. Holmes, Stratford, Conn., assignor to
Oronoque Oil Burner Corporation, New York,
N. Y., a corporation of Delaware

Application June 27, 1930, Serial No. 464,197

7 Claims. (Cl. 158—92)

This invention relates to oil burners, and more particularly, to the types employing a sump for holding the oil to be burned, and means for supplying air under pressure to the combustion chamber.

An object of this invention is to provide an oil burner of the type referred to which is simple in construction, economically made, easily operated and controlled, and yet which will function properly without the necessity for frequently cleaning and adjusting.

A feature of this invention is the provision of means for producing a gyrating or swirling flame whereby the heat of the flame is distributed to all parts of the furnace or stove without the use of a rotating or motor-driven jet.

A further feature is the provision of means and arrangement of parts whereby the parts of the burner adjacent the flame are kept comparatively cool, at least to such an extent that these parts are prevented from being overheated to the point of causing the parts to warp and thus imperfectly fit and improperly cooperate with each other.

And a further feature is the arrangement of the fuel oil feed pipe leading to the sump in such a way that it will be kept cool, thereby preventing carbon from being formed and deposited in the fuel pipe.

And a still further feature is the provision of convenient means for regulating the quantity of fuel oil and also the quantity of air which may be fed to the combustion chamber.

Other objects and advantages will hereinafter appear.

In the accompanying drawings which illustrate one form of this invention, that at present preferred—

Figure 1 is a side view partly in section, taken along the longitudinal center of the device.

Fig. 2 is a plan view of the inner end of the burner with the cover plate removed to show the oil sump and saucer, the deflector rod being shown in section.

Fig. 3 is an end view of the burner looking at the outer end thereof.

Fig. 4 is a sectional view on an enlarged scale of the cover plate which has been removed from Fig. 2.

The burner of this invention comprises a body portion made up of a few simple castings which merely need to be faced and then bolted together. Thus, there is an inner portion or burner proper 10, an intermediate portion 11, and an outer portion 12, having flanges held together by bolts 13.

These portions 10, 11 and 12 are cored and form a conduit for air supplied to the burner under low pressure by a blower 14 comprising an air impeller or fan 15 mounted on the shaft of a selective motor 16 supported on a bracket 17 bolted to the portion 12 of the body. The housing for the fan 15 is formed of two parts 18 and 19, the latter being formed integral with the portion 12 of the body and the former being secured thereto by bolts 20.

When the motor is operated, air is drawn into the blower 14 through an opening 21 in the part 18 of the housing and is forced under pressure through the connected portions 12, 11 and 10 of the body and finally to the combustion saucer, as 15 will appear below.

In order to permit the quantity of air delivered to the burner proper to be varied and so to control combustion without changing the speed of the motor 16, the present invention provides a simple, yet efficient, means for regulating the quantity of air taken into the blower through the opening 21 therein. This means comprises a disk 22 large enough to cover the opening 21 and movable toward or from the margin of the opening 21 to 25 cut-off more or less the free flow of air into the blower. In the form shown herein, the disk 22 is mounted on a screw 23 (carried by a web 24 of the part 18 which extends across the opening 21) in threaded engagement therewith. Hence, by 30 rotating it in one direction or the other, the disk 22 is moved toward or from the opening 21 to change the effective size of the opening 21 and decrease or increase the amount of air which may be drawn into the blower 14 and ultimately supplied to the burner proper.

Fuel oil is supplied to the burner proper, in the form of the invention illustrated herein, by a supply pipe 25 (see Fig. 1) leading to a valve 26 where the quantity of oil-flow may be controlled by automatic means known to the art or by a hand-wheel 27 as shown. From the valve 26, the fuel oil passes through an automatic shut-off valve 28 and various pipes and pipe-fittings 29 to a vertical pipe 30 which extends into the 45 portion 12 of the body.

This pipe 30 is connected to an elbow 31 and the latter is connected to a feed pipe 32 extending through the portions 11 and 10 to be connected in the latter to the burner proper.

This feed pipe 32 is, of necessity, a relatively long pipe and part of it must be located within the furnace adjacent the burner proper. Hence, it would become heated and cause carbon from the oil to adhere to its inner walls. But, this is 55

avoided by the present invention by having the feed pipe 32 located within the portions 10, 11 and 12 where the fresh air forced therethrough by the blower 14 keeps the pipe 32 cool, at least to the extent of preventing the formation of carbon therein, and this in an important feature of this invention.

The burner proper, as stated, is in the portion 10 of the body. It comprises a plate 33 having an annular ring 34 fitting within the circular pot-shaped end 35 of the portion 10 (compare Figs. 1, 2 and 3) while a flange 36 on the annular ring 34 rests on the edge 37 of the pot-shaped end 35. The ring 34 is connected by webs 38 to a saucer 39, the central portion of which has a well or sump 40 in which an elbow 41 connected to the feed pipe 32 is threaded. Hence, fuel oil from the feed pipe 32 may flow into the sump and then over the surface of the saucer 39 where it is ignited and burns.

To induce proper combustion of the fuel oil, the air under pressure in the portions 10, 11 and 12 of the body is, as usual, caused to mix with the products of combustion, but this is done in a novel and extremely advantageous manner in the embodiment of the invention disclosed herein. For, instead of causing a single inwardly directed stream or sheet of air to flow over the surface of the oil container as heretofore, the present invention provides two sets of streams or curtains of air to flow above the surface of the saucer, one set of streams or curtains flowing inwardly while the other flows outwardly, thereby causing the flames to form a narrow ring, receiving air for combustion from both the inner and outer circles of the ring, instead of entirely from the periphery of a circle as heretofore. In the latter case, little if any fresh air could reach the flames and gas in the center of the circle, while in the burner of the present invention, the air supplied from both the inside and outside can thoroughly admix with the gases of combustion and thereby insure proper and complete combustion.

To produce the inwardly directed streams of air, there is provided a cover plate 42 having a seat 43 resting on the annular ring 34 and flange 36 of the saucer 39. This plate has a central circular opening 44 through which the flames may rise and spread to the walls of the furnace. Between its outer and inward circular edges, the plate 42 has a flange 45 extending downwardly toward the surface of the saucer 39 and in actual contact therewith. This flange 45 is provided with two annular series of perforations 46 and 47 through which air under pressure is forced over the surface of the saucer 39 after passing upwardly through spaces 48 between the webs 38 and horizontally under the cover plate 42.

Air is supplied to the center of the burner through a hole 49 in a boss 50 which extends upwardly from the sump at the center of the saucer. This air is caused to be deflected outwardly against the flames by a deflector 51 mounted on a stem 52 extending through the center of the hole 49 in the boss 50 and screw-threaded in a lug 53 on the elbow 41.

The presence of the stem 52 in the hole 49 converts the hole into an annular passage and causes the air to rise along the stem 52 until it is deflected outwardly by the deflector 51.

In operation, to light the burner, the valve 27 is opened to allow fuel oil to flow through the various connections, including the supply

pipe 32, to the sump 40 from which it flows over the surface of the saucer 39. This oil is ignited by throwing a match or burning paper onto the saucer. When the oil begins to burn, the motor 16 is started, causing air under pressure to be forced horizontally and inwardly through the perforations 46 and 47 and upwardly and outwardly through the hole 49 and against the deflector 51. When the oil on the surface of the saucer is properly ignited, the air regulating disc 22 is adjusted until a good flame is obtained, and likewise the hand-wheel 21 of the valve is adjusted to supply the proper quantity of fuel oil.

During the operation of the burner, the horizontal streams of air from the perforations 46 and 47 tend to carry the flames from the saucer inwardly toward the center of the saucer, and do so to a slight extent. But, at the same time, the central streams of air tend to blow the flames outwardly. These two streams of air, therefore, conflict with each other and thus become thoroughly commingled with the burning gases and assist in their combustion.

Moreover, the conflicting streams of air cause the flames rising from the saucer 39 to be agitated and directed to various parts of the walls of the furnace, accomplishing the same result as is produced in other burners by mechanically rotating the burner.

These two opposed streams of air have other advantages, for instance, they keep the parts of the burner adjacent the flames from becoming unduly heated: the air streams escaping through the perforations 46 and 47 keep the surface of the plate 42 from becoming overheated, and consequently, warped; while the air streams escaping through the hole 49 likewise protect the deflector 51 and the stem 52 thereof.

Should the flames rising from the saucer 39 become extinguished by any means, with the resulting cessation of oil consumption, the oil in the saucer 39 will flow over the rim 54 of the saucer and down through the spaces 48 between the webs 38 into the interior of the pot-shaped end 35 of the part 10. This overflow is collected in a trough 55 in the part 10 toward which the walls of the pot-shaped end 35 slope, and from the trough the oil flows by gravity into a pipe 56, and from the latter to a smaller pipe 57 emptying into a pail 58 having a wire loop 59 supported on an arm 60 of the automatic shut-off valve 28. When the pail 58 becomes filled to a predetermined extent, its weight rocks the arm 60 of the automatic valve to shut-off the supply of fuel oil to the burner.

It should be particularly noted that fresh air supplied to the burner proper impinges against the lower or bottom surface of the saucer 39 and keeps the saucer sufficiently cool to prevent warping in spite of the fact that the saucer is located directly beneath the flames.

It should also be clearly understood that the streams of air sweeping across the saucer 39 from the perforations 46 and 47 do not blow down against the surface of the saucer but parallel thereto and slightly spaced above it.

The burner may be supported in any suitable or desirable way, for instance, the part of it which is located within the fire box of the furnace may be supported by a pair of legs 57 bolted to ears 58 on the part 10, while the part outside the fire box is supported by a single leg 59 mounted in the bracket 17 which supports the motor. Thus there is a three-point contact which will support the burner in any desired position regardless of

how uneven the supporting surface may be. The leg 59 is adjustable so that the saucer 39 and the feed pipe 32 may be fixed at the proper level and inclination respectively.

5 Variations and modifications may be made within the scope of this invention and portions of the improvements may be used without others.

Having thus described the invention, what is claimed as new and for which it is desired to obtain Letters Patent, is:—

1. An oil burner having a combustion chamber including a saucer to which fuel oil is delivered to be there ignited and burned and defined by an outer edge; means for conveying air under pressure to the combustion chamber; and means for dividing said saucer into a fuel burning and non-fuel burning section and for causing streams of air to pass successively upwardly over the edge of the saucer next downwardly into the non-fuel burning section and then into the fuel burning section of the saucer through a plurality of orifices at different levels as radially directed streams into the fuel burning section of the saucer, the area of the orifices on the lower level being greater than that of those on the upper level so that the quantity of air being admitted at the level of the saucer is greater than that admitted at a slightly higher level.

2. An oil burner having a combustion chamber including a saucer to which fuel oil is delivered to be there ignited and burned and defined by an outer edge; means for conveying air under pressure to the combustion chamber; and means for dividing said saucer into a fuel burning and non-fuel burning section and for causing streams of air to pass successively upwardly over the edge of the saucer next downwardly into the non-fuel burning section and then into the fuel burning section of the saucer through a plurality of orifices at different levels as radially directed streams into the fuel burning section of the saucer.

3. A liquid fuel burner comprising a casing having an air admission port and affording a pressure air chamber, a burner cup supported by said casing above the bottom thereof and having a peripheral flange, a body member closing the top of said casing and extending down within said burner cup and having air admission ports below the top of said flange, and means, extending through the bottom of said burner cup, for supplying liquid fuel thereto.

4. A liquid fuel burner according to claim 3 in which the body member of the burner cup is provided with air admission ports above said flange in addition to the air admission ports below the top of said flange.

5. An oil burner having a combustion chamber; a substantially flat oil spreader plate in the combustion chamber heated by the products of combustion; an oil sump in the center of the spreader plate also heated by the products of combustion; means for supplying oil to the sump and in a thin film therefrom to the spreader plate, whereby the oil will vaporize as it flows over the spreader plate; means for supplying air to the combustion chamber in the vicinity of the spreader plate to support combustion, said means including an air conduit extending through the oil sump and spreader plate and having an orifice substantially above the spreader plate, said conduit forming a central baffle, said air conduit being in heat-conducting relation with the oil sump to moderate the temperature thereof and avoid flushing of the oil in the sump; and means for blowing the prod-

ucts of combustion horizontally over the spreader plate against said baffle.

6. An oil burner having a combustion chamber; a substantially flat oil spreader plate in the combustion chamber heated by the products of combustion; an oil sump in the center of the spreader plate also heated by the products of combustion; means for supplying oil to the sump and in a thin film therefrom to the spreader plate, whereby the oil will vaporize as it flows over the spreader plate; an air conduit extending through the oil sump and spreader plate and having an orifice substantially above the spreader plate, said conduit forming a central baffle; an air spreader having a stem extending through the air conduit and a spreading disk-like head supported by the stem above the combustion chamber to cause currents of air and products of combustion to be directed upwardly and outwardly from the center of the burner; a circulating-air jacket around the sump and spreader plate to partially cool the oil sump and spreader plate and prevent overheating thereof, said spreader plate having a vertical wall around its periphery; an air deflector adjacent to and around the inner surface of the wall of the spreader plate; and air passages in the deflector plate positioned to direct air streams inwardly and substantially radially over the spreader plate and oil film thereon for supporting combustion, said inwardly directed air streams and products of combustion being forced outwardly and upwardly by the air passing through said central air conduit around said stem and along the surface of said disk-like spreading head and throwing the products of combustion against the walls of the furnace.

7. An oil burner having a combustion chamber; a substantially flat oil spreader plate in the combustion chamber heated by the products of combustion; an oil sump in the center of the spreader plate also heated by the products of combustion; means for supplying oil to the sump and in a thin film therefrom to the spreader plate, whereby the oil will vaporize as it flows over the spreader plate; an air conduit extending through the oil sump and spreader plate and having an orifice substantially above the spreader plate, said conduit forming a central baffle; an air spreader having a stem extending through the air conduit and a spreading disk-like head supported by the stem above the combustion chamber to cause currents of air and products of combustion to be directed upwardly and outwardly from the center of the burner; a shell supporting the spreader plate and forming a circulating-air jacket around the combustion chamber and spreader plate to partially cool the oil sump and spreader plate and prevent overheating thereof, said spreader plate having a vertical wall around its periphery; a cover plate for said shell having a depending flange adjacent to and around the inner surface of the wall of the spreader plate and terminating adjacent the flat surface of the latter; and air passages in said depending flange positioned to direct air streams inwardly and substantially radially over the spreader plate and oil film thereon for supporting combustion, said inwardly directed air streams and products of combustion being forced outwardly and upwardly by the air passing through said central air conduit around said stem and along the surface of said disk-like spreading head and throwing the products of combustion against the walls of the furnace.
